The ornamental design for a vehicle-wheel front face, as shown and described.

DESCRIPTION

FIG. 1 is a perspective view of a vehicle-wheel front face according to my new design;

FIG. 2 is an enlarged front elevational view thereof; and, FIG. 3 is an enlarged side elevational view thereof taken from the left side of FIG. 2, it being understood that the opposite side is a mirror image thereof.

Portions of the wheel depicted in broken line are for illustrative purposes only, and form no part of the claimed design.
